UNITED STATES PATENT OFFICE

133,995

DESIGN FOR A PHOTOGRAPHIC TIMER

Verne W. Franks, Peoria, Ill.

Application January 3, 1942, Serial No. 104,982

Term of patent 3½ years

To all whom it may concern:

Be it known that I, Verne W. Franks, a citizen of the United States, residing at Peoria, in the county of Peoria and State of Illinois, have invented a new, original, and ornamental Design for a Photographic Timer, of which the following is a specification, reference being had to the accompanying drawing, forming part thereof.

In the drawing:

Fig. 1 is a perspective view of my photographic timer; and

Fig. 2 is an end elevational view thereof, the opposite end and side wall being plain.

I claim:

The ornamental design for a photographic timer, as shown and described.

VERNE W. FRANKS.
